UNITED STATES PATENT OFFICE

MELVIN L. CLELAND, OF HASTINGS, NEBRASKA, ASSIGNOR TO G. A. ROTH MANUFACTURING COMPANY, OF HASTINGS, NEBRASKA, A CORPORATION

SIDE AWNING

Application filed January 10, 1929. Serial No. 331,418.

This invention has for its primary object the provision of a side awning for motor vehicles which may be mounted in the window opening exteriorly of the window glass. 5 This thought is a departure from the present type of awning constructions wherein the spring roller on which the canopy of the awning is wound is located interiorly of the window. By locating this roller on the outside, in accordance with my present invention, I am able to provide an awning of much simpler construction and which will function to afford more benefits and advantages to the user. 10 15 In carrying out the idea outlined in the preceding paragraph, I make use of a roller which is mounted in a casing. The latter part serves not only as a protector for the roller and the canopy of the carriage, but also affords a finished and more pleasing appearance. This casing in which the roller is located is carried by arms extending from a tubular rod of telescopic construction, that is carried by side pieces which are positioned in the grooves of the window or door frame. Canopy supporting arms are pivotally connected to these side pieces at the lower portion thereof and are designed for pivotal movement as the canopy is opened 20 or closed, as the case may be. These arms have a connection with a rod or brace located in the outer or free end of the canopy and this connection is, following this invention, adjustable. 25 30 35 With this last mentioned feature is associated an advantage of no little importance. By providing an adjustable connection at this point, one size canopy may be used with several sized windows, and, indeed, when the awning proper overlaps the window opening to some extent, the awning is rendered much more effective.

More detailed and particular objects and advantages of the invention are associated with the mounting of the roller and the provision of the adjustable connections above noted. 40 45

These and other objects and advantages will in part become apparent and in part be

hereinafter stated as the description of the invention proceeds.

For a full and more complete understanding of the invention reference may be had to the following descriptions and accompanying drawings, wherein 55

Figure 1 is a view in perspective of a motor vehicle with an awning made in accordance with my invention applied thereto.

Figure 2 is a vertical section taken about 60 on the line 2-2 of Figure 1 bringing out particularly the disposition of the roller.

Figure 3 is a detail showing in plan of the adjustable connection between the canopy supporting arm and the canopy brace. 65

Figure 4 is a detail showing in perspective, somewhat enlarged, developing the association between the casing and the roller therein. 70

Figure 5 is a view in perspective somewhat diagrammatic with parts being removed, of one side piece, telescopic rod between the side pieces, canopy supporting arms, canopy brace and roller casing. 75

Figure 6 is a detailed view in perspective of one end of the roller receiving casing and develops the mounting of one end of the roller and the means of fastening a cap thereon. 80

Figure 7 is a detailed perspective of a spring member carried by the cap, which spring member functions to retain the cap on the casing. 85

Figure 8 is a view in side elevation of the spring member shown in Figure 7. 85

Figure 9 is a perspective showing of the cap with the spring member affixed thereto. 90

Figure 10 is a fragmentary showing of one end of the canopy bringing out a modified connection between the canopy bracing rod and one of the supporting arms, and 95

Figure 11 is a side elevational view of one end of the supporting arm shown in Figure 10. 100

While a preferred specific embodiment of the invention is herein set forth, it is to be understood I am not to be limited to the exact constructions illustrated and described, because various modifications of these details may be provided in putting the invention into 105

practice within the purview of the appended claims.

Throughout the various figures of the drawings and the following descriptions, like reference characters denote corresponding parts.

In Figure 1 my novel awning is shown as applied to a motor vehicle having a door A, which is provided at the upper portion with a window opening B. The door A at each side of the opening B is formed with grooves 1 in which is a slidable pane of glass 2 which constitutes the window. Felt pieces 3 are interposed between the window glass and the frame of the door A on each side of the former.

I propose to attach my side awning to the door without necessitating the marring or defacing in any manner of the door. This feature is highly advantageous inasmuch as it permits of the removal of the awning when desired without leaving any damaged appearance behind.

Following out this thought, I provide awning supporting instrumentalities which comprise side pieces 4, each of which includes a flange 5 which is adapted to be inserted between felt piece 3 and the door A. The friction created by this insertion is sufficient to normally hold the side pieces in position, particularly, during assemblage and mounting of the awning. The side pieces 4 also include a flange portion 6, which is disposed perpendicularly with respect to the flange 5, and at the lower end the flange 6 is enlarged as shown at 7 for a purpose to be hereinafter more fully set out. The upper portion of the side piece is formed with a projection 8 which is adapted to be seated in one end of a telescopic tube 9 which consists of the part 10 in which is slidably fitted the part 11. Within the telescopic tube 9 may be placed a spring bearing against the projection 8 and against the end of the part 11, the spring assuring firm engagement between the side pieces 4 and the felt in which the side pieces are inserted.

A casing 12 of the construction clearly shown in Figures 4 and 5 is held in position by arms 13 which are fastened to the casing in any approved manner as by the rivet shown at 14; these arms 13 being clamped to the telescopic tube 9 by the arrangement shown at 15, which bolt and nut construction permits of the removal of the casing 12 when occasion demands.

A cap 16 fits over one end of the casing 12 and is affixed thereto by any suitable means such as by rivets insertable through the holes shown at 17. An awning or canopy 18 is taken up by a spring roller 19 of a well known construction, which roller is located in the casing 12. The free end of the canopy 18 is provided with an overlapped portion 20 in which is located a bracing or stiffening mem-

ber 21 which is formed with overturned ends, as shown at 22. In the present instance, the overturned ends 22 are of a square construction, the ends of which are notched as indicated at 23 to provide what is in effect a thread on the portion 22.

An arm 24 has an opening in one end which fits over the portion 22 and which is held in position thereon by nuts 25 which are threaded on the thread 23. The construction just described is at one end of the canopy and it is understood there is a duplication of this arrangement at the other side of the window opening. The lower end of the rod 24 is joined to the portion 7 of the side piece 4 by means of a pin and ratchet connection indicated generally at 26, and described in my co-pending application, Serial No. 312,356, filed October 31, 1928. This connection permits of the holding of the arm in any adjusted position through cooperation with the spring roller 19.

A preferred construction of the casing 12 and method of fastening the cap thereon is shown in Figures 6, 7, 8 and 9. In this embodiment, a roller supporting portion 28 is cut and bent from the case as are the two ears 29. The ears 29 are bent inwardly toward each other at right angles to the casing. The supporting portion 28 is provided with an aperture to receive the usual pin on the roller.

The cap 16 is provided for the purpose of excluding dirt, water, and other detrimental materials from the interior of the casing 12, this casing being mounted exteriorly of the window to which the canopy 18 is applied; and because the cap 16 is removable, ready access to the interior of the casing 12 is obtained. It will be understood that each end of the casing 12 is covered with such a cap.

Figures 6, 7, 8 and 9, as above mentioned, show a preferred construction of the casing, and the method of fastening the cap 16 thereon. This embodiment will now be described in more detail, it being understood that the cap fitted to each end of the casing 12 is exactly similar to the other, so that only one of these caps needs to be described.

It will be observed that, in Figures 7, 8 and 9, there is fitted into the cap 16, and secured thereto in suitable manner, as by a rivet 31, a disc member 30, which is provided with lugs 32 formed conveniently by cutting through the member 30, part way along its diameter, as shown in Figure 2, and then bending a portion of the member 30 along the cuts to form lugs 32. These lugs 32 are formed by bending opposite edges of the respective cuts outwardly from the same surface of the disc member 30. These lugs, or off-set portions, are, therefore, oppositely disposed, so that a turning of the cap 16, subsequent to the placing of the latter over the casing 12, will cause the off-sets 32 to engage the ears 29 to hold the cap in position on the

casing and to prevent the cap being removed from the casing by longitudinal movement while the portions 32 remain in engagement with the ears 29.

5 It will be understood that the roller is held in position in this form by first bending the portion 28 at one end of the casing 12, and then slipping the roller carrying its canopy into the casing 12, and engaging the pin on the roller in its aperture in the supporting portion 28, after which a corresponding portion is bent at the other end of the casing to engage the roller pin on that end. The ears 29, are also formed in each end, and each cap 10 adapted to fit over the ends is provided with the disc 30 as above described.

In Figure 4 there is indicated a supporting portion 28^a, corresponding to the supporting portion 28 of Figure 6, which is provided 20 with an aperture, similarly as above described, through which the roller pin 37 is seated. The supporting portion or member 28^a in this case is secured in any suitable manner to the casing 12, as by riveting, welding, soldering, or the like. In this form of 25 the construction, each cap 16 is secured to the ends, as pointed out above, the caps forming a dust- and water-proof seal for the protection of the ends of the roller and canopy, 30 which, however, can be readily removed to give access to the interior of the casing 12 in the event that the roller 19 should become displaced from its position.

In Figures 10 and 11 I have shown a 35 slightly modified connection between the canopy bracing rod 21 and the supporting arm 24. In this modification the upper end of the arm 24 is of a hub like formation as shown at 33, providing the opening 34. A set 40 screw 35 is mounted in hub portion 33 and is adapted to bear against the rounded portion 36 of the stiffening member 21. When this construction is used the arm 24 may be placed in any position with respect to the round rod 45 36 and held in that position by tightening the set screw 35.

Having thus described my invention, what I claim as new and desire to secure by Letters Patent of the United States, is:

50 1. A side awning of the class described, comprising, in combination, side pieces which are designed to be fitted in the side grooves of a window opening of a motor vehicle, telescopic instrumentalities for holding the side pieces in position in the grooves, a casing carried by said last named instrumentalities, and a canopy construction located within the casing and adapted to be extended therefrom.

60 2. In a side awning construction of the class described, the combination with a roller, and a canopy thereon, of a rod in one end of the canopy, said rod having threaded extremities, arms for holding the canopy in any one of a plurality of extended posi-

tions, and adjustable connections between the arms and the threaded extremities of the rod in the end of the canopy.

3. In a side awning of the class described, the combination with a roller, means for mounting the roller on the body of a motor vehicle, a canopy on said roller having a free end, a rod affixed to the free end of the canopy and extending thereacross to render the same rigid, of arms adapted to be pivotally mounted on a vehicle body for holding said canopy in any one of a plurality of extended positions, and an adjustable connection between the arms and said rod extending across the end of the canopy, said connection consisting of the ends of the rod which are turned back on themselves to provide portions overlapping the canopy, said portions being threaded, and nut means co-operating with the threaded portions for holding the arms in position thereon.

4. A side awning of the class described, comprising, in combination, side pieces adapted to be held in the grooves of a window opening by frictional engagement with the walls of said grooves, a telescopic rod extending between said side pieces, resilient means tending to expand said telescopic rod whereby the pressure holds the side pieces in position in the grooves, arms extending 90 from said telescopic rod, and a casing carried by said arms, the casing being adapted to hold a spring roller having a canopy mounted thereon.

5. A side awning of the class described, comprising, in combination, side pieces 100 adapted to be held in the grooves of a window opening by frictional engagement with the walls of said grooves, a telescopic rod extending between said side pieces, resilient means tending to expand said telescopic rod 105 whereby the pressure holds the side pieces in position in the grooves, arms extending from said telescopic rod, a casing carried by said arms, a spring roller having a canopy 110 mounted thereon, mounted in said casing, and means associated with the lower ends of the side pieces for holding the canopy in an extended position.

6. A side awning for motor vehicles of 115 the class described, comprising, in combination, a casing, means for mounting the casing exteriorly of a window opening of a motor vehicle, a canopy take-up device within the casing, a canopy associated with the 120 take-up device, a cap member for the casing, and spring means for detachably fastening the cap member on the casing.

7. A casing for supporting a canopy carrying roller adapted to be mounted on motor 125 vehicles, comprising, in combination, a tubular member deformed at one end to provide a roller supporting member and ears, the said ears constituting a means whereby a cap is detachably secured to the end of the tube, 130

a cap, and spring means in the cap engaging the ears aforesaid.

8. In a side awning of the class described, the combination with a roller, means for mounting the roller on the body of a motor vehicle, a canopy on said roller having a free end, a rod affixed to the free end of the canopy and extending thereacross to render the same rigid, of arms adapted to be pivotally mounted on a vehicle body for holding said canopy in any one of a plurality of extended positions, an adjustable connection between the arms and said rod extending across the end of the canopy, said connection consisting of the ends of the rod which are turned back on themselves to provide portions overlapping the canopy, said portions being smooth, and means cooperating with the smooth portions for holding the arms in position thereon.
9. A side awning of the class described, comprising in combination, side pieces adapted to be held in the grooves of a window opening by frictional engagement with the walls of said grooves, a telescopic rod extending between said side pieces, arms extending from said telescopic rod, a casing carried by said arms, the arms rigid with the casing, and provided with clamping means adapted to hold said telescopic rod in varied adjustment, a spring roller having a canopy mounted thereon mounted in said casing, and means associated with the lower end of the side pieces for holding the canopy in an extended position.
10. A side awning of the class described, comprising in combination, side pieces adapted to be held in the grooves of a window opening by frictional engagement with the walls of said grooves, slidable members extending between said side pieces, arms extending from said slidable members, a casing carried by said arms, the arms connected to the casing, and provided with clamping means adapted to hold the slidable members in adjusted position, a spring roller having a canopy mounted thereon, mounted in said casing, and means associated with the lower end of the side pieces for holding the canopy in an extended position.
11. A side awning of the class described, comprising, in combination, side pieces adapted to be held in the grooves of a window opening by frictional engagement with the walls of said grooves, members between said side pieces, arms extending from said members, a casing carried by said arms, the arms connected to the casing, and provided with holding means adapted to hold the members in adjusted position, a spring roller having a canopy mounted thereon, mounted in said casing, and means associated with the lower end of the side pieces for holding the canopy in an extended position.

In testimony whereof I affix my signature:

MELVIN L. CLELAND.
